[57] **CLAIM**

The ornamental design for a combined vehicle hood shield and deflector, as shown and described.

DESCRIPTION

FIG. 1 is a top plan view of a combined vehicle hood shield and deflector showing our new design;

FIG. 2 is a front elevation view thereof;

FIG. 3 is a bottom plan view thereof;

FIG. 4 is a side elevation view thereof;

FIG. 5 is a top rear perspective view thereof on a reduced scale mounted on a vehicle which is fragmentarily shown in broken lines for illustrative purposes only and forms no part of the claimed design; and, FIG. 6 is a side elevation view of FIG. 5.

The dash lines on the surface of the combined vehicle hood shield and deflector in the drawings represents stitching.

FIG. 1

FIG. 2

FIG. 3
